UNITED STATES PATENT OFFICE.

FRANK E. BECKMAN, OF HAVERHILL, MASSACHUSETTS, ASSIGNOR TO UNITED SHOE MACHINERY CORPORATION, OF PATERSON, NEW JERSEY, A CORPORATION OF NEW JERSEY.

METHOD OF MAKING SOLES.

Original application filed March 16, 1920, Serial No. 366,265. Divided and this application filed December 1, 1920. Serial No. 427,526.

To all whom it may concern:

Be it known that I, FRANK E. BECKMAN, a citizen of the United States, residing at Haverhill, in the county of Essex and State 5 of Massachusetts, have invented certain new and useful Improvements in Methods of Making Soles; and I do hereby declare the following to be a full, clear, and exact description of the invention, such as will enable others skilled in the art to which it 10 appertains to make and use the same.

The present invention relates to methods of making soles for boots and shoes and more particularly to a method of moulding or 15 breaking down the margins of soles for turn shoes.

Heretofore it has been the practice to break down the margins of turn soles by the application of progressive pressure, the 20 margin of the sole being fed progressively past the pressure applying or moulding instrumentalities of a machine such, for example, as the Goodyear power moulding machine disclosed in Letters Patent of the 25 United States, No. 1,110,637, granted September 15, 1914, to William C. Meyer. It has been found difficult to practice the above 30 described method upon soles having extremely pointed toes without distorting the toe and thus spoiling the lines of the shoe when finished.

The object of the present invention is to avoid the disadvantage of the method just described, by providing an improved method 35 of moulding the margins of turn soles, the practice of which will eliminate all danger of distorting the toe of the sole during the moulding operation.

With this object in view, the present invention consists in the novel method of 40 moulding the margins of turn soles herein-after described and then particularly pointed out in the appended claims.

In carrying out the method, it is preferred 45 to practice one of the steps thereof by means of a moulding machine or press such as that disclosed in the inventor's co-pending application filed March 16, 1920, Serial No. 366,265, from which the present application 50 is a division. Another step involved in the method constituting the present invention consists in moulding by progressive pressure, the portions of the sole margin at the

opposite lateral edges of the sole. Preferably, but not necessarily, this step is performed after the completion of the toe moulding operation. This step may be practiced by any suitable machine such, for example as that disclosed in said patent to William C. Meyer, hereinbefore referred to. 60

The present method will be explained with the assistance of the accompanying drawings illustrating a machine having the same construction and mode of operation as the machine disclosed in the inventor's 65 above-mentioned co-pending application Serial No. 366,265.

In the drawings, Figure 1 is a view, in front elevation, of the machine; Fig. 2 is a view, in side elevation, of the mould supporting members of the machine; Fig. 3 is a plan view of the upper or male mould supporting head, detached; Fig. 4 is a plan view of the lower or female mould, detached; Fig. 5 is a perspective view of the 75 fore part of a turn sole after its toe has been moulded; and Fig. 6 is a cross-sectional view of the sole shown in Fig. 5, the view being taken on the line 6—6 of said figure. 80

To facilitate a clear understanding of the method constituting the present invention, the construction of the machine which it is preferred to employ to perform the toe moulding operation will be described in detail. This machine is provided with devices for moulding the toe end of the sole. The moulding devices comprise a mould couple, comprising male and female moulds so shaped as to produce, about the toe end 90 of a sole placed therebetween, an accurately moulded margin according to the size and style of the sole. Furthermore, because of the confinement of the sole between the moulds, a sole which may be out of shape, 95 because of inaccurate rounding, is reshaped to the exact outline required for perfect shoe-making. The moulds are of such proportions as to break down the margin of the sole for a distance of about one and one-half inches from the tip of the toe, i. e., to about the tip line. The soles are in temper when subjected to the operation of the toe moulding machine and are left under a brief sustained pressure to permit the 100 moulded margin to set. Thus, after re-

moval from the machine, the moulded soles may be handled without harm to the toe end, since the broken down margin is stiff and immovable.

5 The machine illustrated in the drawings, comprises a table 10 supported at a convenient height and provided with a base block 12 having oppositely disposed ears 14. The lower or female mould block 16 is 10 movably secured to the base block 12 by screws 17 threaded into definitely located receiving bores in the ears 14.

Above the mould block 16 is a vertical bearing 18 carried at the forward end of the 15 overhanging frame 20 which rises from the table at the rear end of the base block 12. A plunger 22 is fitted to slide in this bearing, to the upper end of which is suitably jointed the rod 24 of an eccentric strap 26 embracing 20 an eccentric 28 on the forward end of a power shaft 30 driven by a pulley 32. Two journals for the shaft 30 rise from the frame 20 of which the forward one 34 only is shown. The revolution of the shaft 30 is 25 controlled by a clutch (not shown), operated by a treadle attached to the rod 36, designed to provide for a sustained pressure on the sole placed between the moulds as is common to presses of this general type.

30 The upper or male mould is secured to the lower face of a split block or head 38 having the construction shown in Figs. 1 and 3, a bolt 40 serving to clamp it on the lower end of the plunger 22. A centering pin 42 35 (dotted lines Fig. 1) serves to locate the head on the plunger and a pair of guide pins 44 engage bores 46 in the lower mould block 16. The male mould is thus exactly centered over the female mould.

40 In order to avoid frequent adjustment for size or style it is desirable to provide each mould block with a series of moulds, each couple differing from the others. In the illustrated embodiment of the invention each 45 block is provided with three moulds representing three different sole widths. The lower block 16 is formed in one piece the female moulds being produced by recesses 48 of the required formation, i. e., generally 50 triangular, in its upper face. The male moulds 50 are independent of each other, each mould being received and located on the lower face of the block 38 by a centering pin 52 (dotted lines Fig. 2) and removably 55 held in position by a set screw 54 passing through an ear 56 which bears against the front face of the block 38. The machine will be equipped with such additional mould couples as may be required for all the styles 60 and widths used in any particular factory and it will be observed that the mountings described provide for speedy interchangeability. This forms an important feature of the invention.

65 The moulds are so designed as to break

down the margin of the sole to the extent shown in Figs. 5 and 6. For good shoe-making the break on the grain side of the sole should be directly opposite the shoulder on the flesh side. Accordingly the inner 70 wall 58 (Fig. 4) of the female mould corresponds in shape to the shoulder on the sole and its height is equal to the depth of the shoulder. The outer wall 60 corresponds in shape to the edge of the sole. This feature 75 is not essential but it is desirable since this wall serves as a gauge to correctly locate the toe of the sole above the cavity formed by the inner wall 58. The lower surface 80 (Fig. 1) of the male mould is so proportioned as to form the break on the grain side opposite the shoulder on the flesh side when the descent of the plunger 22 forces the two moulds together. The oblique walls 59 and 61 of the two moulds are of such angularity 85 to the horizontal surfaces as may be required to give the desired offset to the margin of the sole which may have been shouldered for incorporation in either a mock welt or a feather edged turn shoe. 90

In using the press a turn sole, which has first been fitted with a marginal shoulder by a suitable stock fitting machine such, for example, as disclosed in Letters Patent of the United States to Frederic E. Bertrand No. 95 1,030,704, granted June 25, 1912, is placed with its toe end within and in contact with the wall 60 of the proper sized lower mould. The body portion of the sole extends outwardly through the open end of the mould 100 recess and may be held by the operator without danger of injury to him. The clutch is then thrown in and the upper mould 50 descends forcing the shoulder down within the lower wall 58 thus reshaping the toe should 105 this be necessary. The oblique walls 59 and 61 of the lower and upper moulds grip the margin outside the shoulder and cooperate to break it down to the extent permitted by their obliquity to the horizontal surfaces of 110 the mould couple. It will be observed, as shown more particularly by Fig. 4, that the ends of the female mould walls are flared at the open end of the mould so as to avoid an injurious break at the tip line and provide 115 for a merging of the moulded margin into the unmoulded margin to the rear thereof.

As hereinbefore explained, the portions of the sole margin at the opposite lateral edges of the sole may be moulded or broken down in any convenient manner either before or after the toe moulding operation. Preferably this step in the method of moulding the sole margin will be performed by the progressive pressure type of machine here- 120 fore mentioned.

The present inventor believes himself to be the first to practice the herein described method of completely moulding the margins of turn soles having pointed toes, partly by 125

a sustained moulding pressure and partly by progressive pressure. Those skilled in the art will recognize the advantage of moulding the margin at the toe of a pointed toe sole by means of a sustained pressure which will effectively prevent distortion and act to reshape the toe if this is required.

Having thus described the invention and the preferred method of practicing it, it is definitely stated in its true scope in the following claims.

What is claimed is:

1. The method of making turn soles which includes the steps of moulding the margin about the end of the sole by a sustained pressure, and moulding the margin at the sides of the sole.
2. The method of making turn soles which includes the steps of breaking down the margin about the toe with a single sustained moulding pressure, and breaking down the margin at the sides with a progressive pressure.
3. The method of making turn soles which includes the steps of moulding the margin about the toe while the sole is held from movement relatively to the moulding means,

and moulding the margin at the sides by feeding the sole past suitable pressure applying means.

4. The method of making turn soles which consists of producing a marginal shoulder, moulding the margin outside said shoulder by means of a sustained pressure extending about the toe and rearward from its tip to substantially the tip line, and moulding the remaining portions of the margin outside the shoulder by a progressive pressure.

5. The method of making turn soles which includes the steps of applying moulding pressure to the margin simultaneously throughout its length about the tip of the toe, and applying progressive pressure to portions of the sole margin at the opposite lateral edges of the sole.

6. The method of making turn soles which consists in breaking down the margin of the sole in two stages, to wit: at the lateral edges thereof and about the tip of the toe, the latter stage employing simultaneous pressure throughout the margin from one side of the tip of the toe to the other.

FRANK E. BECKMAN.
